TENSIONING DEVICE

Guy L. Matthews and Harry L. Diehl, Chicago,
Ill.; said Matthews assignor to said Diehl

Application July 30, 1932, Serial No. 626,343

13 Claims. (Cl. 265—1)

This invention relates to tensioning devices, and particularly to a device for tensioning cords, strings, gut, etc., wherein the degree of tension placed on the cord or string may be positively determined.

One object of the present invention is to provide a tensioning device which is relatively light in weight, portable, easy to handle, and wherein the tension exerted by the use of the device is completely and entirely under direct control of the operator.

Another object of the invention is to provide a tensioning device wherein the degree of tension exerted is positively indicated to the operator.

Another object of the invention is to provide a tensioning device which may be operated by a minimum expenditure of physical effort.

Another object of the invention is to provide a tensioning device which will enable one to obtain uniform tensioning of strings, as for example, in the stringing of a tennis racket, or the like, without long practice and experience in the work.

A further object of the invention is to provide a tensioning device having cord or string gripping means associated therewith, which enables the operator to easily hold the cord while tensioning, and which provides suitable protection against crushing or otherwise damaging the cord.

A still further object of the invention is to improve devices of the character described in sundry details hereinafter referred to and particularly pointed out in the appended claims.

One embodiment of the present invention is shown for illustrative purposes in the accompanying drawing, in which

Fig. 1 is an elevational view of our improved tensioning device illustrating its use in stringing, and tensioning the strings of a tennis racket, or the like;

Fig. 2 is an enlarged elevational view of a portion of the tensioning device illustrated in Fig. 1, having portions thereof broken away to facilitate the showing of certain structure embodied in the device, the view being taken substantially as indicated by the line 2—2 of Fig. 3; and

Fig. 3 is a longitudinal sectional view taken substantially as indicated by the line 3—3 of Fig. 2.

The racket shown in Fig. 1, in connection with which the use of the present invention is illustrated, comprises a frame 5 including a handle 6, the frame 5 being provided with main strings 7 and cross strings 8 threaded through portions of the frame 5 in the usual manner.

The illustrative embodiment of the present invention as shown in the drawing comprises a

main supporting member or frame indicated as a whole by the numeral 9, and comprises a shank portion 11 having a hand grip 12 formed at one of its ends, and a head 13 formed at the opposite end thereof, the head 13 having a cord holding surface 14 extending laterally and substantially transversely to the shank portion 11 of the supporting member, and having a longitudinally extending flange portion 15 offset with respect to the shank portion.

For securing a string, gut or cord, as for example, the cross string 8 of a tennis racket, against the cord holding surface 14, a gripping jaw 16 is slidably mounted on the shank portion 11 between guide flanges 17 and 18 formed thereon, the jaw 16 being arranged in a manner to have a rectilinear movement with respect to the shank portion. The gripping jaw 16 is provided on its string or cord engaging face with a compressible material 19 such as rubber, felt, or the like, for providing an efficient frictional engagement with the cord or string without damage thereto by reason of any crushing effect which otherwise might result from the gripping of the cord or string between the cord holding surface 14 of the head 13 and the gripping jaw 16.

For actuating the gripping jaw, a movable hand grip 21 in the nature of a bell crank lever is pivotally mounted intermediate its ends at 22 on a laterally extending lug 23 formed on the supporting member or frame 9, the short arm 24 of the bell crank lever or movable hand grip 21 being provided with an elongated aperture 25 adapted to receive a pivot pin shown in the present instance as a screw 26 mounted in the gripping jaw 16 at the lower or opposite end thereof from the string or cord engaging face material 19, and for separating the hand grips 12 and 21 to release the string, a spring 27 is positioned between the grips preferably adjacent the pivotal connection 22.

It will be observed from the foregoing description that the cord or string 8, for example, may be conveniently and quickly positioned between the cord holding surface 14 and compressible material 19 of the jaw face, and that by drawing the hand grips 12 and 21 together, a force or pressure will be exerted upon the string in a manner to hold it securely between the surface 14 and material 19 with very little effort on the part of the operator. The head 13 is provided with a plurality of guide pins 28 for properly positioning the cord with respect to the surface 14 and face of the jaw 16, and it will be observed that upon releasing the operator's grip, the spring 55

27 will separate the hand grips 12 and 21, and that through its connection with the short arm 24 of the movable hand grip 21, the gripping jaw 16 will be moved to disengage the compressible material 19 from engagement with the cord.

5 Mounted on the shank portion 11 in a manner to have a rectilinear sliding movement with respect thereto is a pressure member or indicator actuating shoe designated as a whole by the numeral 29, the said shoe having a contact portion 31 formed thereon in substantial alignment with the body of the device and in spaced relation with respect to adjacent gripping or engaging portions of the head 13 and jaw 16.

10 15 For slidably mounting the pressure member 29 on the shank portion 11 of the supporting member or frame 9, the member 29 is provided with an elongated aperture or slot 32 adapted to receive a bolt 33 screw-threaded into the shank portion 11, and for maintaining the member 29 in substantial alignment with the main supporting member 9 or body of the device, the pressure member 29 is provided with guide portions 34 and 35 positioned on opposite sides of the shank portion 11 in a manner to have a sliding engagement therewith.

20 25 For yieldingly maintaining the pressure member 29 and its contact portion 31 in predetermined normal position with respect to the head 13 and in spaced relation with the cord holding surface 14 thereof, a resilient member shown in the present instance as a coiled spring 36 is positioned between the inner side of the cord holding portion 14 of the head 13 and the inner side 30 35 of the contact portion 31 of the pressure member 29, the spring 36 being secured against lateral displacement by means of studs or pintles 37 and 38 formed on the pressure member 29 and head 13, respectively, and adapted to enter the opposite open ends of the spring.

40 45 The spring 36 shown in the present instance is of the compression type and acts to normally separate the contact portion 31 of the pressure member 29 and the cord holding surface 14 of the head 13, and to maintain the lower end of the slot 32 in engagement with the pin 33 as clearly shown in Fig. 3.

50 55 Rotatably mounted in the flange portion 15 of the head 13 is a shaft 39, to one end of which is secured an indicator finger 41 adapted to cooperate with a scale 42 (see Figs. 1 and 2) formed on the flange portion 15 and which may be provided with suitable graduations and indicia to indicate various degrees of tension. To the opposite end of the shaft 39 is secured a pinion 43 adapted to mesh with a rack 44 rigidly secured adjacent one of its ends to the contact portion 31 of the pressure member 29, the arrangement being such that any rectilinear movement of the pressure member 29 with respect to the head 13 will be transmitted through the rack 44, pinion 43 and shaft 39 to the indicator finger 41 in a manner to move the free end of the finger along the scale 42 formed on the flange portion 15 of the head 13. Thus, it will be observed that the spring 36, through its connections with the shaft 39 as above described, serves to yieldingly resist rotation of the shaft, and permit movement thereof and of the indicator finger 41 only in accordance with the movements of the pressure member 29.

60 65 70 75 In the stringing and tensioning the strings of a tennis racket, for example, the operation of the device is substantially as follows: the string or gut may be threaded through apertures formed

in the frame of the racket and provided for that purpose, each run or strand of the gut after tensioning being anchored in any suitable manner as by means of an awl 45 (Fig. 1) as is the usual practice. The strand or run of the gut 5 to be tensioned, as for example the cross string 8a shown in Fig. 1, is then gripped between the cord holding surface 14 of the head 13 and the compressible material 19 of the gripping jaw 16 after the manner shown in Fig. 1, the tensioning 10 device, preferably, being positioned with respect to the racket frame 5 substantially as shown in Fig. 1, with the contact portion 31 of the pressure member 29 in engagement with the outer surface or edge of the frame 5 and the flange portion 15 of the head 13 and a flange 46 formed on the pressure member 29 extending on opposite sides of the racket frame 5 in a manner to maintain the contact portion 31 against lateral displacement with respect thereto. With the 15 various parts of the tensioning device and racket in the positions above described, a swinging movement of the outer ends of the hand grips 12 and 21 about the point of engagement of the contact portion 31 with the racket frame 5 as a fulcrum, and in the direction indicated by the arrow 47 of Fig. 1, will cause a tensioning of the string or gut 8a and a pressure to be exerted by the contact portion 31 against the edge of the racket frame 5 in a manner to cause the pressure member 29 and rack 44 to move relatively to the head 13, such movement of the rack 44 causing the pinion 43 and shaft 39 to rotate, thereby moving the indicator finger 41 along the scale 42 in a manner to indicate the degree of tension 30 exerted upon the particular run or strand of gut being operated upon, after which, and while the tension on the string 8a is maintained, the awl 45 may be withdrawn from the position illustrated in Fig. 1 and inserted in the aperture 48 40 of the frame 5 in a manner to wedge the tensioned strand therein until the gut is again threaded across the racket, and the tensioning device applied thereto at the opposite side of the frame for tensioning the next strand or run of 45 the gut in the manner above described.

45 50 55 60 65 70 75 80 85 90 95 It will be observed from the foregoing description that the present invention provides a tensioning device by the use of which suitable tension on the strings may be obtained without great physical effort on the part of the operator due to the leverage possible by reason of the relative positions of the cord and racket frame engaging portions of the device, and that by reason of the connection between the indicator finger 41 and the pressure member 29, forming a part of the tensioning mechanism, the various strands or runs of the cord or gut may be provided with measured uniform tension which is most desirable in many instances particularly in tennis rackets, or the like, and it will be observed also that by use of the present invention, a most efficient stringing or restringing job may be accomplished by an operator without having had any particular amount of practice or experience in work of this kind.

80 85 90 95 It will of course be obvious that the tensioning device of the present invention may be used in tensioning of the main strings 7 of a racket as well as the cross strings thereof, its use in connection with the latter, as shown in Fig. 1, being merely illustrative.

Obviously, the present invention is not limited to the precise construction and arrangement shown and described as the same may be vari- 75

ously modified. Moreover, all the features of the invention need not be used conjointly as the same may be used to advantage in various different combinations and sub-combinations.

5 What we claim as new and desire to cover by Letters Patent is:

1. In a tensioning device, the combination of a head, a manually actuated gripping jaw having a compressible material on its face cooperable with said head for securely holding a cord therebetween, and a yieldable pressure member mounted on said head and movable with respect thereto, said member having a contact portion spaced from adjacent cord holding portions of said head and jaw and adapted to engage a relatively fixed portion of an article on which the tensioning device is used.

2. In a tensioning device, the combination of a main supporting frame having a hand grip formed thereon, a head formed on said supporting frame, a movable hand grip pivotally mounted on said frame, a gripping jaw pivotally connected to said movable hand grip and having a compressible material on its face cooperable with said head for securely holding a cord therebetween, and a pressure member mounted on said head and movable with respect thereto, said member having a contact portion spaced from the cord securing portions of said head and jaw, said contact portion being adapted to engage an article on which the tensioning device is used.

3. In a tensioning device, the combination of a head, a manually actuated gripping jaw engageable with said head for securely holding a cord therebetween, a pressure member mounted on and movable with respect to said head and having a contact portion adapted to engage an article on which the tensioning device is used, said portion being spaced from the engaging portions of said head and jaw, resilient means for resisting the movement of said pressure member, and tension indicating means operatively connected to said pressure member in a manner to be actuated thereby.

4. In a tensioning device, the combination of a head, a manually actuated gripping jaw cooperable with said head for securely holding a cord therebetween, a pressure member mounted on and movable with respect to said head and having a contact portion adapted to engage an article on which the tensioning device is used, said portion being spaced from adjacent cord holding portions of said head and jaw, and resilient means for resisting the movement of said pressure member with respect to said head.

5. In a tensioning device, the combination of a head, a manually actuated gripping jaw engageable with said head for securely holding a cord therebetween, cord engaging guide pins mounted on said head, a pressure member mounted on and movable with respect to said head and having a contact portion adapted to engage an article on which the tensioning device is used, said portion being spaced from the engaging portions of said head and jaw, and resilient means for resisting the movement of said pressure member with respect to said head.

6. In a tensioning device, the combination of a main supporting frame, a head forming a part of said frame, a manually actuated gripping jaw engageable with said head for securely holding a cord therebetween, a pressure member mounted on said supporting frame and movable with respect to said head, said pressure member having

7. In a tensioning device, the combination of a main supporting frame having a hand grip formed thereon, a head formed on said frame, a movable hand grip pivotally mounted on said frame, a gripping jaw operatively related to said movable hand grip in a manner to be actuated thereby and engageable with said head for securely holding a cord therebetween, a pressure member mounted on said frame and movable with respect to said head, said pressure member having a contact portion spaced from the engaging portions of said head and jaw, resilient means for resisting the movement of said pressure member, a graduated scale on said frame, and an indicator finger associated with said scale and operatively connected to said pressure member in a manner to be actuated thereby.

8. In a tensioning device, the combination of a main supporting frame having a hand grip formed thereon, a head formed on said frame, a movable hand grip pivotally mounted on said frame, a gripping jaw pivotally connected to said movable hand grip and engageable with said head for securely holding a cord therebetween, a pressure member mounted on said frame and having a contact portion spaced from the engaging portions of said head and jaw, resilient means for resisting the movement of said pressure member, a graduated scale on said frame, and an indicator finger associated with said scale and operatively connected to said pressure member in a manner to be actuated thereby.

9. In a tensioning device, the combination of a main supporting frame having a hand grip formed thereon, a head formed on said frame, a movable hand grip pivotally mounted on said frame, a gripping jaw connected to said movable hand grip and having a rectilinear movement with respect to said supporting frame, said jaw being cooperable with said head for securely holding a cord therebetween, a pressure member mounted on said frame and having a contact portion spaced from the engaging portions of said head and jaw and movable with respect to said head, resilient means for resisting the movement of said member, an indicator finger pivotally mounted on said head, and means operatively connected to said finger and pressure member for actuating the finger in accordance with the movement of said pressure member.

10. In a tensioning device, the combination of a main supporting frame having a hand grip formed thereon, a head formed on said frame, a movable hand grip pivotally mounted on said frame, a gripping jaw connected to said movable hand grip and having a rectilinear movement with respect to said supporting frame, said jaw being engageable with said head for securely holding a cord therebetween, a pressure member mounted on said frame and having a contact portion spaced from the engaging portions of said head and jaw and having a rectilinear movement with respect to said head, resilient means operable between said member and head for resisting the movement of said member, an indicator finger pivotally mounted on said head, and means operatively connected to said finger and pressure member for actuating the finger in accordance with the movement of said pressure member.

11. In a tensioning device, the combination of a main supporting frame having a hand grip formed thereon, a head formed on said frame, a movable hand grip pivotally mounted on said frame, a gripping jaw connected to said movable hand grip and having a rectilinear movement with respect to said supporting frame, said jaw being engageable with said head for securely holding a cord therebetween, a pressure member mounted on said frame and having a contact portion spaced from the engaging portions of said head and jaw and having a rectilinear movement with respect to said head, resilient means operable between said member and head for resisting the movement of said member, a graduated scale formed on said head, an indicator

75 a contact portion spaced from the engaging portion

finger pivotally mounted on said head adjacent said scale, and means operatively connected to said finger and pressure member for actuating the finger in accordance with the movement of said pressure member.

11. In a tensioning device, the combination of a main supporting frame having a hand grip formed thereon, a head formed on said frame and having a flange portion extending longitudinally thereof, a movable hand grip pivotally mounted on said frame, a gripping jaw connected to said movable hand grip and having a rectilinear movement with respect to said supporting frame, said jaw being engageable with said head for securely holding a cord between the jaw and head, a pressure member having a flange formed thereon and movably mounted on said frame, a contact portion on said pressure member between said flange and the flange portion of said head, said contact portion being spaced from the engaging portions of said head and jaw and movable with respect to said head, a spring operable between said member and head for resisting the movement of said member and contact portion, a graduated scale formed on said head, an indicator finger pivotally mounted on said head adjacent said scale, and means operatively connected to said finger and pressure member for actuating the finger in accordance with the movement of said pressure member with respect to said head.

12. In a tensioning device, the combination of a main supporting frame having a hand grip formed thereon, a head formed on said frame, a movable hand grip pivotally mounted on said frame, a gripping jaw connected to said movable hand grip and having a rectilinear movement with respect to said supporting frame, said jaw being engageable with said head for securely holding a cord therebetween, a pressure member mounted on said frame and having a contact portion spaced from the engaging portions of said head and jaw and having a rectilinear

movement with respect to said head, resilient means operable between said member and head for resisting the movement of said member, a graduated scale formed on said head, a shaft rotatably mounted in said head, an indicator finger mounted on said shaft and operatively related to said scale, a pinion mounted on said shaft, and a toothed rack carried by said member and operatively connected to said pinion for rotating said shaft and moving said finger in accordance with the movement of said pressure member.

13. In a tensioning device, the combination of a main supporting frame having a hand grip formed thereon, a head formed on said frame and having a flange portion extending longitudinally thereof, a movable hand grip pivotally mounted on said frame, a gripping jaw connected to said movable hand grip and having a rectilinear movement with respect to said supporting frame, said jaw being engageable with said head for securely holding a cord between the jaw and head, a pressure member having a flange formed thereon movably mounted on said frame, a contact portion on said pressure member between said flange and the flange portion of said head, said contact portion being spaced from the engaging portions of said head and jaw and movable with respect to said head, a spring operable between said member and head for resisting the movement of said member and contact portion, a graduated scale formed on said head, a shaft rotatably mounted in said head, an indicator finger secured to said shaft and operatively related to said scale, a pinion secured to said shaft, and a toothed rack carried by said pressure member and operatively connected to said pinion for rotating said shaft and moving said finger along said scale in accordance with the movement of said pressure member with respect to said head.
